DISCHARGE LAMP AND MEANS FOR OPERATING THE SAME

John S. Smith, Hazel Crest, and Floyd Dawson,
Chicago Heights, Ill.

Application December 28, 1936, Serial No. 117,706

8 Claims. (Cl. 40—130)

Our invention relates in general to electrical apparatus and has more particular reference to an improved gaseous conduction device and improved means for energizing the same.

5 An important object of the invention is to provide a gaseous conduction device, namely a lamp, having improved means for suppressing unwanted emanation produced by the operation of the lamp, which emanation may deleteriously 0 affect the operation of sensitive equipment, such as a radio receiver, in the vicinity of the discharge device.

Another important object of the invention is 5 to provide a discharge lamp adapted for operation in the vicinity of sensitive electrical equipment without interfering with the operation of such sensitive equipment; a further and more specific object of the invention being to provide 10 a discharge lamp for use as a warning signal or an advertising sign or other attention arresting device on a vehicle, including means for energizing the lamp from the electrical power system of the vehicle without, however, interfering with the operation of a sensitive electrical 15 device, such as a radio receiver, also powered from the electrical system of the vehicle.

Another important object is to provide a discharge lamp having screening means for suppressing undesired electrical disturbance emanating from the lamp when in operation; a further 20 object being to provide lamp screening means which does not interfere with the visibility of the lamp when in operation.

Another important object is to screen a discharge lamp to suppress electrical disturbance 25 generated by the operation of the lamp and at the same time improve the visibility of the lamp.

Another important object is to utilize foraminous metallic means for the purpose of screening 30 a discharge lamp in order to suppress electrical disturbance caused by the operation of the lamp, the screen being of a character to improve the visibility of the lamp; a further object being to utilize woven wire fabric as a screening means 35 for a device of the character mentioned.

Another important object is to provide improved means for operating a discharge lamp from a uni-directional electrical power source 40 of relatively low potential.

50 Another important object is to provide an improved power transformer for delivering electrical power at relatively high potential from a power source of relatively low potential, said transformer means having low potential portions arranged in novel fashion permitting the

power transformation to be accomplished at maximum efficiency.

Another important object is to provide a power transformer having a high potential winding and a plurality of low potential windings inductively coupled with the high potential winding, said low potential windings comprising conductor coils arranged in parallel interspaced relationship whereby the transformer is of minimum over-all size and wherein the inductive relation 5 between each of said low potential windings and the high potential winding is substantially identical so as to permit the device to be used at maximum efficiency as a full wave transformer.

Another object of the invention resides in the 15 manner of applying low potential windings in a transformer device by winding the several conductors forming the low potential windings in such a way that the corresponding portions of each of said windings are parallel and immediately adjacent to each other.

These and numerous other objects, advantages, and inherent functions of the invention will be apparent from the following description, which, taken in connection with the accompanying 20 drawing, discloses a preferred form of the invention.

Referring to the drawing:

Figures 1 and 2 are diagrammatic representations of electrical systems embodying our present invention;

Figure 3 is a perspective view illustrating the construction and method of making a transformer unit forming a part of the system shown in Figure 1;

Figures 4 and 5 are sectional views taken substantially along the lines 4—4 and 5—5 in Figure 1; and

Figure 6 is a perspective view illustrating a modified form of lamp embodying our invention.

To illustrate our invention we have shown on the drawing an electrical system 11 comprising means for delivering electrical energy at relatively high potential by transforming energy derived from a relatively low potential source 13, 45 and although in the illustrated embodiment we have shown this delivered energy utilized for the operation of a gaseous conduction element 15, it will be obvious that this phase of our invention at least is not necessarily restricted to the particular load to which the delivered energy is applied. We have, however, illustrated our invention as applied particularly to the operation of the gaseous conduction lamp 15, containing improvements which render it well adapted for use 50 55

as a warning signal or other attention arresting device on a vehicle in which the low potential power source 13 used in energizing the system 11 forms a part of the electrical system 5 of the vehicle. In such an arrangement the power source 13 may comprise a storage battery of the character usually employed in automotive vehicles for ignition, lighting, and for energizing electrical equipment as, for instance, 10 a radio receiver, ventilating fan, horn and the like forming a part of the vehicle equipment.

Our present invention relates also to the provision of a lamp embodying the gaseous conduction element 15 and includes the provision of an 15 improved lamp mounting 17 which is formed with means for screening the element 15 in order to suppress, confine and/or eliminate electrical disturbance, initiating at the lamp element 15 when the same is in operation, in order to prevent such 20 disturbance from deleteriously affecting the operation of sensitive equipment, such as a radio receiver mounted in the vehicle.

The power transforming system 11 comprises a transformer 19 having a high potential winding 21 and low potential windings 23 preferably comprising a plurality of sections 25, 27 inductively coupled with the winding 21, the coupling between the winding 21 and the sections 25 and 27 being substantially identical. In the illustrated 30 embodiment the sections 25, 27 of the low potential windings are connected together at one end as at 29 and, through a suitable control switch 31, to one side of the power source 13. The opposite ends of the winding sections 25 and 27 35 are connected respectively to the stationary contacts 35 and 37 of a circuit changer 33 which is preferably a vibrator having, in addition to the stationary contacts 35 and 37, a reed 39 suitably anchored in position to oscillate between the stationary contacts and alternately engage the same. The reed 39 may be and preferably is anchored at one end and electrically connected in any suitable manner, as indicated at 41, with the power source 13, this connection 41 being preferably 45 accomplished by grounding the anchored end of the reed and grounding the side of the power source 13 opposite from the switch 31. The reed is also provided with an armature 43 in position to be influenced by an actuating coil 45 which 50 in turn is connected in any suitable manner, as between one of the stationary contact sets and the power source 13, in order that the coil 45 may be periodically energized, by connection with the power source, and de-energized as a result of the 55 vibration of the reed. In the illustrated embodiment the reed actuating coil 45 is connected between the stationary contact set 37 and the connection 41.

The reed 39 is preferably positioned so that the 60 armature 43 is normally offset with respect to the coil 45 so that, when the apparatus is at rest, the reed engages and makes electrical contact with one or other of the stationary contact sets 35, 37, thus placing one of the windings 25, 27 in 65 circuit with the power source 13. In the illustrated embodiment, the reed 39 is thus biased to engage the contact set which is not connected with the coil 45, i. e., the contact set 35. Upon closure of the switch 31, a surge of electrical 70 current will take place through the low potential winding section 25 thus placed in circuit with the power source. At the same instant the coil 45 will be energized in a direction to draw the 75 reed 43 out of engagement with the contact set 35 and project the same into engagement with

the contact set 37. It will be noted that the winding section 27 is at all times in circuit with the power source 13 through the winding 45. However, this winding 45 is of relatively high resistance, so that little current may flow initially 5 through the winding section 27. As soon as the reed 39 disengages the contact set 35, current flow through the winding section 25 will be discontinued. When the reed engages the contact set 37, however, the high resistance winding 45 10 will be short-circuited and a relatively large flow of current will be permitted to flow through the winding section 27. As soon as the reed 39 engages the contact set 37, the coil 45 is short circuited and becomes de-energized, thereby releasing 15 the armature 43 so that the reed, under its normal bias, may return toward the contact set 35, thus disengaging the contact set 37 and discontinuing the relatively large current flow in the winding section 27. In this manner a relatively 20 large current flow may be initiated alternately through the winding sections 25 and 27 which, due to the inductive relationship between said winding sections and the winding 21, will result in the development of relatively high alternating 25 or fluctuating potential between the opposite ends of the winding 21. A condenser 38 may be connected between each of the contact sets 35 and 37 and the reed 39 to reduce arcing at the contacts as the circuits are interrupted. 30

The development of the relatively high value alternating potential may be accomplished by connecting the low voltage winding sections 25, 27 in other than the manner illustrated. For example, in Figure 2 of the drawing we have illustrated a modified wiring diagram wherein one end of the winding section 27 is connected together with the opposite end of the winding section 25, said interconnected ends being connected through the switch 31 with the power source 13. 40 In this arrangement the free end of the winding section 27 is connected with the stationary contact set 37, while the opposite free end of the winding section 25 is connected with the stationary contact sets 35. The alternating frequency 45 of the potential developed in the winding 21 in the arrangement shown in Figure 1 will be approximately double the alternating frequency produced from the arrangement shown in Figure 2 assuming that the vibrating period of the 50 reed 39 is the same in both arrangements. The amplitude of the alternating potential developed from the arrangement shown in Figure 1, however, will be somewhat less than that of alternating potential developed from the arrangement shown in Figure 2. 55

One of the features of the power transforming system 11 resides in the construction of the transformer 19. This transformer comprises a core 47 of any suitable or preferred form upon 60 which the high potential winding 21 is arranged preferably as a plurality of layers 49 suitably insulated from each other and from the core 47. A layer of insulation 51 is preferably applied upon the winding 49 and the low potential winding sections 25, 27 are applied outwardly of said layer of insulation 51. The sections 25, 27 each comprise an electrical conductor, the section 25 comprising the conductor 55 and the section 27 comprising a conductor 57. These conductors 65 are arranged in parallel adjacent relationship and so wound together in place, as clearly illustrated in Figure 3 of the drawing. Each of the corresponding portions of the conductors 55, 57 occupies parallel adjacent positions and the in- 70 75 75

ductive relationship of both sections 25 and 27, with respect to the high potential winding 21, is substantially identical. The conductors 55, 57 may be arranged to form a plurality of layers 59 as clearly shown in Figure 3 of the drawing, each layer insulated from the other by insulation 60.

As heretofore stated, our invention relates also to the provision of an improved gaseous conduction lamp and mounting 17, which is formed with means for screening the element 15 to prevent the emission of electrical disturbance caused by the operation of the lamp element.

To this end, the mounting 17 comprises a preferably metallic casing in which the lamp element 15 is suitably mounted, the casing 17 having an opening through which the lamp element is visible. This opening may be covered by any preferred translucent or transparent material, such as the glass pane 61, which of course may be supported and secured on the casing 17 in any preferred fashion. In order to prevent the emanation of undesirable electrical disturbance, we also enclose the lamp in a suitable shield, preferably comprising a metallic material, which is arranged in such a way as to avoid obscuring the visibility of the lamp through the opening of the casing. Where the casing itself is of metallic material, it may form a part of the screen. The screen preferably comprises a metallic network, preferably in the form of a woven wirescreen 63, although of course the metallic network may be formed otherwise than as a woven wire screen. The screen 63 may of course be embedded in the transparent pane 61 and formed therein in any suitable convenient or preferred manner. However, the screen element 63 may also be conveniently produced as an element separate from the pane 61 and arranged in the assembly immediately behind the pane and between it and the lamp element 15. We prefer also that the screen 63 be electrically connected, as by contact at its edges with the casing 17, and to this end, as shown in Figures 1 and 4 of the drawing, the casing 17 comprises a rectangular, elongated, preferably metallic box having suitable mounting lugs 65 and having one side open. The box internally is provided with means forming seats 67 at the open side for receiving the transparent element 61 and the screen element 63, and these parts may be held in place by any suitable clip means, such as the frame 69 adapted to be secured on the box as by means of the fastening screws 71 or otherwise, the frame having portions 73 adapted to overlie the marginal edges of the pane 61 and keep it and the screen element 63 in place. The lamp 15 may be a gaseous conduction tube of usual form having electrode chambers 75 formed at its opposed ends. The usual connection wires 77 may extend from the electrode chamber 75, and one of these wires 77 is preferably grounded on the casing 17, as at 79, while the other connection wire is preferably heavily insulated and led out of the casing 17 through an insulating sleeve 81 mounted in a wall of the casing in any preferred manner. In order to provide for energizing the lamp 15, the conductor 77, which extends from the casing through the insulating sleeve 81, is electrically connected to one end of the high potential winding 21, while the other end of said winding is connected in any suitable manner to the casing 17, thus making an electrical connection between the conductor 77 which is grounded at 79 on the casing 17.

The winding 21 may of course be connected to the casing 17 by means of an electrical conductor, although where the system of our present

invention is mounted in an automotive vehicle, the casing 17 may be electrically connected to the frame of the vehicle and grounded thereon, and the winding 21 likewise may be grounded to the frame of the vehicle in order thus to complete the lamp energizing circuit.

In Figure 6 of the drawing we have shown a modified form of lamp mounting wherein the casing 17 is of generally wedge-shaped configuration providing a chamber 83 at the apex of the wedge-shaped casing, and a somewhat elongated chamber 85 which, if desired, may be curved as shown in the wider portions of the casing. The apical portions of the wedge-like casing are preferably rounded as at 87 and provide a window 89 opening into the chamber 83. The chamber 83 also has an additional window 91 in a side of the casing, extending at right angles with respect to the walls containing the window 89, while the chamber 85 likewise has a window 93, preferably extending substantially in a common plane with the window 91. The chamber 83 may contain a suitable lamp, for example an incandescent lamp, of the character usually employed in vehicle warning lamps. The window 91 also may carry a red bull's eye lens, while the window 89 may be fitted with a transparent, preferably glass, window pane. Suitable bracket means 95 also may be attached to the casing for the purpose of mounting it in position as on the frame of a vehicle, and the bracket means may also serve to support a license tag in position to be illuminated by light penetrating from the lamp within the chamber 83 through the window 89. Light rays from the same lamp penetrating the window 91 may serve as a tail light.

The compartment 85, however, may serve as a housing for a gaseous conduction lamp 97 adapted to be intermittently energized as a stop signal, by connecting the same in the manner shown in Figure 1 of the drawing. The window 85 may contain a suitable transparent pane in conjunction with a screen for suppressing electrical disturbances emanating from the lamp 97 when in operation, and the pane and screen in the window 85 may be arranged and mounted in the manner heretofore mentioned in connection with the lamp shown in Figure 4 of the drawing.

An important feature of our present invention resides in the fact that a foraminous wire screen 63, when arranged in front of a gaseous conduction lamp, does not impair the visibility of the lamp, providing the screen is of sufficiently wide mesh. On the contrary, the presence of a foraminated screen actually improves the visibility of the lamp by eliminating halation. At the same time, if a screen having excessively large openings is employed, the suppression of electrical disturbance as well as the anti-halation characteristics of the lamp is impaired. We consequently prefer to employ wire mesh of the order of eight strands per linear inch, so that the openings in the screen are one-eighth inch squares.

It is thought that the invention and its numerous attendant advantages will be fully understood from the foregoing description, and it is obvious that numerous changes may be made in the form, construction and arrangement of the parts without departing from the spirit or scope of the invention or sacrificing its attendant advantages, the form herein described being a preferred embodiment for the purpose of exemplifying our invention.

Having thus described our invention, what is claimed as new and is desired to be secured by

Letters Patent of the United States is as follows:

1. A lamp comprising a casing adapted to receive a gaseous conduction lamp element therein, said casing having an opening for displaying the lamp element, and a metallic screen in said opening for substantially covering said lamp, said screen comprising a metallic layer having foraminations therein of sufficient size to avoid impairment of the visibility of the lamp through said opening.
2. A lamp comprising a casing adapted to receive a gaseous conduction lamp element therein, said casing having an opening for displaying the lamp element, and a metallic screen in said opening for substantially covering said lamp, said screen comprising a woven wire netting forming a metallic layer having foraminations therein of sufficient size to avoid impairment of the visibility of the lamp through said opening.
3. A lamp comprising a metallic casing adapted to receive a gaseous conduction lamp element therein, said casing having an opening for displaying the lamp element, and a metallic screen in said opening whereby said screen, together with said metallic casing, provides a shield for screening the lamp element against the emission of electrical disturbances caused by the operation of the lamp element, said screen comprising a metallic layer having foraminations therein of sufficient size to avoid impairment of the visibility of the lamp through said opening.
4. A lamp comprising a metallic casing adapted to receive a gaseous conduction lamp element therein, said casing having an opening for displaying the lamp element, and a metallic screen in said opening whereby said screen, together with said metallic casing, provides a shield for screening the lamp element against the emission of electrical disturbances caused by the operation of the lamp element, said screen comprising woven wire fabric electrically connected with the metallic casing.
5. A lamp comprising a casing adapted to receive a gaseous conduction lamp element therein, said casing having an opening for displaying the lamp element, and a metallic screen in said opening for substantially covering said lamp, said screen comprising a metallic layer having foraminations therein of sufficient size to avoid impairment of the visibility of the lamp through said opening, the lamp element comprising a tube electrically connected at one end on the casing and provided with a conductor at the other end
6. A lamp comprising a casing having partition means forming a plurality of lamp chambers within the casing on opposite sides of the partition means, said casing having window openings in a side thereof opening into each of said chambers, another side of said casing having a window opening upon at least one of said chambers, means for mounting a lamp in said chamber, means for mounting a gaseous conduction lamp in the other chamber, and a foraminous metallic screen in the window opening of the chamber containing the gaseous conduction lamp.
7. A lamp comprising a casing, means forming a plurality of windows in a side of said casing, one of said windows having a colored window element therein, said casing having means to support a lamp therein in position to shine through said colored window element, means to support a gaseous conduction lamp element in said casing in position to shine through another of said window openings, and a metallic screen disposed in said casing in position with respect to the gaseous conduction lamp element to suppress electrical disturbances emanating therefrom when the same is in operation, said metallic screen including a portion extending in the window opening through which said gaseous conduction lamp element is visible, and said portion having foraminations of a size adapted to reduce halation of light rays emitted by the gaseous conduction lamp element without impairing the visibility of said rays through the window.
8. A lamp comprising a casing, means forming a plurality of compartments within said casing, a gaseous conduction lamp element in one compartment, lamp means in said other compartment, both of said compartments having openings through which light from said lamp element and said lamp means may pass outwardly of the said compartments, and a metallic screen in the opening of the compartment containing the gaseous conduction lamp element, said screen comprising a metallic layer having foraminations therein of sufficient size to avoid impairment of the visibility of the lamp through said opening containing the screen.

JOHN S. SMITH.
FLOYD DAWSON.
